STRUCTURAL UNIT

Winfred E. Wilson, Los Angeles, Calif.

Application March 28, 1939, Serial No. 264,554

3 Claims. (Cl. 20—92)

This invention relates to wall construction, and more particularly to an interlocking structural unit for walls and roofs of buildings, and for other structures.

The general object of the invention is to provide an improved interlocking structural unit, which may be easily assembled to form a wall structure capable of effectively resisting and supporting applied forces and loads.

Another object is to provide a wall structure comprising a plurality of interlocking units arranged in series in end-to-end relationship and with each series interlocked with an adjacent series, whereby each series is capable of resisting forces, such as moment, thrust, and shear, independently of the adjacent series.

Another object is to provide a structural cellular unit comprising a frame and walls of thin sheet material secured to the top and bottom of said frame, which walls aid materially in carrying stress incident to the primary function of the unit.

A further object is to provide a structural unit of the character stated, which, by means of its prefabrication and ease of assembly, will effect a considerable saving of time and cost in the construction of a wall.

Other objects and advantages will appear hereinafter.

With the above and other objects in view, the invention consists in the novel and useful provision, formation, construction, and relative arrangement of parts, members and features, all as disclosed in certain embodiments in the accompanying drawings, described generally, and more particularly pointed out in the claims.

In the drawings:

Figure 1 is a plan view of an arched roof composed of my interlocking structural units.

Figure 2 is an edge view of Figure 1.

Figure 3 is a fragmentary longitudinal section of two of my interlocking structural units, taken on line 3—3 of Figure 1, showing the joint for interlocking the adjoining ends of said units.

Figure 4 is a transverse vertical section taken on line 4—4 of Figure 1, showing one of the joints for interlocking two adjoining series of my structural units.

Figure 5 is a horizontal section taken on line 5—5 of Figure 4.

Figure 6 is a view like Figure 3, showing a modification of the joint for interlocking the adjoining ends of two of my interlocking units.

Figure 7 is a plan view of the modification of the joint shown in Figure 6.

Figure 8 is an edge view of a wall and roof of a building composed of my structural units,

Figure 9 is a side view of a modification of my invention showing the same applied to adjoining ends of the wooden beams of a wooden building,

Figure 10 is a view like Figure 9 showing my invention applied to the adjoining ends of the steel beams of a structural steel building, and,

Figure 11 is a perspective of my unit in cellular form.

Referring more particularly to the drawings, in which corresponding parts are designated by the same reference characters in all of the figures, my invention comprises generally a cellular unit 1 with interlocking connecting elements 2 on the ends thereof for connecting said ends to the ends of other units; interlocking connecting elements 3 on the corners of said unit for connecting said corners to the sides of other units; 20 and interlocking connecting elements 4 on the sides of said unit for connecting said sides to the corners of other units. The cellular unit 1 includes a frame 5 constructed with side members 6, end members 7, intermediate longitudinal 25 brace 8, lower well 9 secured to the lower edges of said frame members and brace, and upper wall 10 secured to the upper edges of said frame members and brace, said walls being formed of suitable thin sheet material. The frame members 6 and 7, brace 8, and walls 9 and 10 are secured in proper assembled relation in known fashion by glue, nails, screws, or other devices, or a combination thereof.

The connecting elements 2 are secured to the 35 ends of the unit 1 at the lower and upper edges thereof, and said elements are in the form of what is known as a continuous or piano hinge, with spaced knuckles, each element 2 forming one-half of one of such hinges, so that the 40 knuckles of each element on the ends of each unit 1 are adapted to fit between the knuckles of a complementary element 2 on an end of an adjoining unit 1, in intermeshing relation to receive a loose pin or rod 11, which serves to interlock the two intermeshing halves of such 45 hinge together, whereby the ends of adjoining units 1 are interlocked.

The interlocking elements 3 on the corners of the units 1 are in the form of hinge knuckles 50 and are so positioned that when the ends of two adjoining units 1 are interlocked, the elements 3 on the corners of said units rest one above the other in spaced relation to receive therebetween an interlocking element 4, also in the form of 55 a hinge knuckle, on one side of another unit, so

that a pin 12 may be introduced through said intermeshing elements 3 and 4 to interlock said third unit at one side between its ends to the adjoining side of said first two units at the interlocked ends of said first two units, shown in Figures 1, 4 and 5. The corners of each unit 1 are beveled, as at 13, to provide spaces 14 to receive the interlocking elements 3 and 4 so that the sides of the units may be brought together, as shown in Figures 1, 4 and 5.

The operation, uses and advantages of my invention are as follows:

The units 1 are arranged in series in end-to-end relation and their adjoining ends interlocked by the intermeshing interlocking elements 2 and the pins 11 inserted respectively through each complementary pair of said elements. Each end-to-end series of units 1 is placed in side-to-side relation with another end-to-end series, and said adjoining end-to-end series are interlocked in side-to-side relation, with the units 1 of each series staggered with relation to the units of the other series, by the intermeshing interlocking elements 3, on the adjoining ends of each two units of each series, with the interlocking element 4, on the side of a unit of an adjoining series, and the pins 12 inserted through each of said intermeshing interlocking elements 3 and 4, as illustrated in Figure 1.

My units may be readily and easily assembled to form the walls and roofs of buildings or other wall structures. My interlocking elements 2 may be employed to connect adjoining ends of steel or wooden beams in a building structure.

In the modification of my invention shown in Figures 6 and 7, the interlocking elements 2 on the ends of the units 1 are formed with square-cornered knuckles 15 to receive split or double wedge-shape pins 16 and 17, which wedge tightly together in the intermeshing knuckles and take up all looseness and end play between the ends of adjoining units 1 and make the structure rigid.

In the modification of my invention shown in Figure 9, my interlocking elements 2 and pins 11 are shown connecting the adjoining ends of wooden beams 18 of a wooden building construction, with the elements 2 formed with securing plates 19, which are secured to the edges of said beams by bolts 20, which extend through said

beams and said plates, and also through shear plates 21 under said securing plates to aid in transferring the stress from the elements 2 to said beams 18, there being spring washers 22 placed between the nuts 20' of the bolts 20 and the securing plates 19 to compensate for shrinkage of the beams 18.

In the modification of my invention shown in Figure 10, my interlocking elements 2 and pins 11 are shown connecting the adjoining ends of steel beams 23 of a structural steel building construction.

I claim:

1. An interlocking structural unit formed with interlocking elements on the ends thereof to intermesh with like interlocking elements on the ends of adjoining units, means for interlocking said intermeshing interlocking elements, and interlocking elements on the corners of said unit to intermesh with interlocking elements on the corners of adjoining units and with interlocking elements on the sides of other units, and means for positively interlocking said intermeshing interlocking elements on said corners and said sides of said units for positively preventing lateral displacement of the units interlocked side-by-side.

2. An interlocking structural unit including means on the ends thereof to interlock with the ends of adjoining units, and interlocking elements on the corners of said unit to intermesh with interlocking elements on the corners of adjoining units and with interlocking elements on the sides of other units, and positive means for interlocking said intermeshing interlocking elements on said corners and said sides of said units for positively preventing lateral displacement of the units interlocked side-by-side.

3. An interlocking structural unit including means on the ends thereof to interlock with the ends of adjoining units, and knuckles on the corners of the said units to intermesh with knuckles on the corners of adjoining units, and with knuckles on the sides of other units, and pins extending respectively through said intermeshing knuckles for positively preventing lateral displacement of the units interlocked side-by-side by said pins and said intermeshing knuckles, through which said pins extend.

WINFRED E. WILSON.
